DRAWING INSTRUMENT FOR LETTERING
AND DIMENSIONING

Gregory S. Dolgorukov, Detroit, Mich.

Application October 27, 1944, Serial No. 560,593

7 Claims. (Cl. 33—174)

1

This invention relates to drawing instruments and more particularly to an improved lettering guide. The present application is a continuation-in-part of my co-pending application, Serial No. 482,432, filed on April 9, 1943, Patent No. 2,379,791, granted July 3, 1945.

One of the objects of the present invention is to provide an improved lettering guide with the aid of which neat and accurate lettering may be done without the necessity of first drawing any guide lines therefor.

Another object of the invention is to provide a lettering guide which can be successfully used for both pencil and ink work.

A further object of the invention is to provide a lettering guide with the aid of which the necessity of setting and using a compass for drawing circles around letters and numerals, such as those commonly used in indicating "revisions" or "piece numbers" on drawings, is eliminated, and such circles may be drawn rapidly and centered properly with respect to the letter or numeral without the necessity of finding the centers therefor.

A still further object of the invention is to provide an improved lettering guide which enables its user to "box" certain dimensions or words without the use of a triangle and without slowing down lettering and dimensioning by the necessity of laying aside the lettering tool and reaching for an instrument such as a triangle which is usually laid aside when lettering.

A still further object of the invention is to provide an improved lettering guide enabling the user to letter and dimension in a four-size font of letters, as well as in four single-size fonts of letters.

A still further object of the invention is to provide an improved lettering guide providing for selectively positioning note lines at one of four distances bearing a predetermined relationship to the height of the note line.

It is an added object of the present invention to provide an improved lettering guide of the foregoing character which is of a simple one piece construction, is dependable and convenient in use, and is relatively inexpensive to manufacture.

Other objects of this invention will appear in the following description and appended claims, reference being had to the accompanying drawings forming a part of this specification, wherein like reference characters designate corresponding parts in the several views.

Fig. 1 is a view showing my improved lettering guide in a position at a straight edge and for use with pencil.

2

Fig. 2 is a sectional view taken in the direction of the arrows on the section plane passing through the line 2—2 of Fig. 1, said view showing the guide in a position for pencil lettering.

Fig. 3 is a view similar in part to Fig. 2, but showing the guide turned on the paper end-over-end into a position for ink lettering.

Fig. 4 is a view showing samples of various characters of the four-size font producable with the guide, as well as samples of characters of various single-size fonts; also circles and rectangles producable with the same guide in their proper space relationship with respect to the characters inscribed therein.

15 Before explaining in detail the present invention it is to be understood that the invention is not limited in its application to the details of construction and arrangement of parts illustrated in the accompanying drawings, since the invention 20 is capable of other embodiments and of being practiced or carried out in various ways. Also it is to be understood that the phraseology or terminology employed herein is for the purpose of description and not of limitation, and it is not 25 intended to limit the invention claimed herein beyond the requirements of the prior art.

The lettering guide disclosed herein is of a combination slot construction and is provided with a set of longitudinally adjacent or merging slot portions, the respective widths of which and their mutual axial arrangement are so selected that by shifting the guide along a straight edge of a T-square, a triangle, or the like, the user may letter through these slot portions a line of lettering characters which, although belonging to the same font or complete assortment of lettering characters, have different heights and even axial arrangement, as is the case, for instance, with line letters, capitals therefor, fractions, and tolerances written in two lines. It is an important 40 advantage of my improved guide that neither the guide nor the T-square need be moved vertically until it is necessary to write another line, and in lettering a line the guide is simply moved to the right or to the left along the T-square to bring the desired slot portion to the place where the lettering character of a different height than the last lettered characters has to be lettered.

Referring to the drawing, the lettering guide 50 illustrated therein comprises a body 10 made preferably in the form of a flat rectangular strip of substantially transparent material, such as cellulose nitrate or cellulose acetate, commercially known as "Celluloid," said body being provided 55 with a straight guiding edge 11, which edge is

moved in operation of the guide along the straight edge 13 of a T-square, a triangle or the like. Parallel to said straight edge 11, there is provided a combination slot generally indicated by the numeral 12, said slot being composed of a plurality, in the present instance four, of longitudinally adjacent slots or slot portions 14, 15, 16, and 17, having their longitudinal edges parallel to said straight edge 11, thus making the entire slot 12 also parallel to said edge 11, as mentioned.

The slot 14 is the narrowest slot, its width being in the nature of the basic width from which the width of the remaining slots is derived. In the present embodiment of the invention I prefer to make the width of the slot 15 equal to approximately 1.5 times, slot 16—2 times, and slot 17—2.5 times of the width of slot 14, adding approximately .015"-.020" to the widths of the slots 14 and 15, and approximately .020"-.030" to the widths of the slots 17 and 16 to allow for the thickness of the pencil point.

Slots 14 and 15 may have their lower edges 14b and 15b extending along the same straight line, and slots 15 and 16 may have their upper edges 15a and 16a extending along the same straight line. The slot 17 may have its upper and lower edges 17a and 17b disposed at an equal transverse distance from the corresponding edges of slot 14. Thus the slots 14, 16 and 17 have their respective longitudinal axes arranged along the same straight line, and therefore are co-axial, while the slot 15 is, in effect, offset co-axially with respect to the other slots.

By virtue of the above construction the guide enables lettering therethrough lettering characters of a four-size font, i. e., a font or assortment the various characters of which may have as many as four different heights. Thus, if the slot 14 is adapted for lettering therethrough characters of .10" high, slot 15 may be used for producing capitals of .15" high for line letters produced through slot 14. The slot 16 may be used for bracketing the lettering matter produced through the slot 14, for double line tolerances, for bracketing dimensions produced through the slot 14, (this being possible since the slots 14 and 16 are co-axial) as well as for lettering other characters extending an equal distance below and above the letters producable through the slot 14. The slot 17 may be used for lettering therethrough fractions for numerals lettered through the slots 14 or 16.

In addition to the above, the above described construction provides for lettering through a single guide in four single-size fonts, i. e., in four sizes of lettering characters having no interrelation between their respective heights.

Making the combination slot in the form of mutually merging slot portions, instead of closely adjacent but non-communicating slots, has an important advantage in manufacture by making it possible to cut all four slot portions in a single operation without withdrawing the cutting tool and then bringing it up to work again. It should be understood, however, that the longitudinal order of the slot portions may vary from what is employed in the present embodiment, consistent with the requirement that as little shifting or longitudinal moving of the guide as possible should be required for the general run of lettering.

It is often required in drafting work to draw a circle around a numeral or a letter, such as in drawing "piece numbers" on an assembly draw-

ing, or in applying "revision letters" thereto. Such circles are usually drawn with the aid of a compass, either before or after the character is written. Difficulties are encountered in either case. In drawing the circle after the character is lettered, i. e., circumscribing the circle around the character, it is very difficult to get the position of the center correctly and the circle usually appears placed eccentrically, which is readily apparent and very unsightly on a drawing. In lettering the character in ink into a circle, i. e., inscribing it into a circle, the ink runs under the cloth through the hole made by the needle point of the compass, producing a spot which has to be removed. Moreover, the necessity of putting aside the lettering instruments and getting hold of a compass and adjusting it to the required radius breaks into the continuity of lettering operations and is a source of wasted time and an annoyance to the draftsman.

My improved lettering guide eliminates the above disadvantages and enables the draftsman to draw circles around numerals or letters in an accurate and speedy manner, properly centered and without laying aside lettering instruments or breaking the continuity of lettering operations. In accordance with the invention, the body 19 is provided adjacently to said combination slot 12 with a number of round openings. Said openings are arranged to have their geometric centers on the straight line 20 forming a continuation of the axes of the slots used for lettering the characters which are to be circumscribed with the respective circles. In the present embodiment of the invention there are provided two circles 18 and 19, both of said circles having their centers on the straight line 20 constituting an axis of the slots 14, 16 and 17. By virtue of such a construction, after a desired character or characters are lettered through one or several of said slots, the guide is moved along the straight edge 13 of the T-square, the desired hole centered around the character (which is incomparably easier to do than to guess the position of the center for an undrawn circle), and a circle is drawn with the same lettering instrument that was used for lettering the character, by moving its point along the edges of the selected round hole. It is very important to appreciate that with my improved guide it is not necessary to move the T-square for drawing such circles, and that drawing of the same is done with the same position of the T-square as for lettering the respective character. In the present embodiment of the invention in order to satisfy specific requirements of one system of lettering used in a number of drafting rooms in this country the circles 18 and 19 have their diameters selected to draw circles approximately three-eighths and one-half inch in diameter, respectively. However holes for drawing circles of other diameters to satisfy other requirements or regulations may be provided. For the sizes of circles commonly used on average assembly and other drawings the actual diameter of the hole should be approximately .015"-.020" larger than the diameter of the desired circle to provide clearance for the pencil, similarly to the clearance provided in the slots. It should be appreciated that in lettering notes through the slots or otherwise, it is customary to hold the pencil inclined as in writing, while in drawing circles through the holes the pencil is customarily held nearly vertical. With the thickness of the lettering guide such as .060" which is customary for drafting instruments and which is sufficient to prevent annoying sliding of the guide

under the T-square, lettering through a narrow unchamfered slot with a pencil held in a naturally inclined position would not only be annoying and inconvenient but would produce a much narrower or lower line of letters, and the center line of such a line would be raised considerably. On the other hand, since in drawing circles the pencil is held nearly vertical, lack of chamfer would not affect materially the diameter of the circle drawn therethrough or the position of its center. Thus, a lack of chamfer on the edges of the body of a lettering guide at the slot, at least along the lower edges thereof, and particularly in a lettering guide of a customary thickness, not only makes slot-lettering difficult and annoying, but also requires arranging the holes in such a manner as to have their centers disposed below the continuation of the center line of the slot portion which is served by the particular hole.

In my improved lettering guide means are provided which make the same guide successfully useable both for pencil and for ink work. In the present embodiment of the invention said means are exemplified by an ink clearing groove 21 provided on the upper surface 10a of the guide, and running through the entire length thereof. I prefer to make such groove approximately .035" deep, and its width such as to extend beyond the transverse extent of the slot 12 and round holes 18 and 19, thus ensuring clearing the ink of any characters lettered therethrough. The upper edge 21a of the groove 21 is at such a distance from the slot 12 as to enable one to clear the wet ink of the upper line and letter the next lower line at least through the slots 14 and 15 without waiting for the upper line written through the same slots to dry. Of course, increasing the width of the body 10 permits increasing the width of the groove 21 to extend its transverse extent to distances ensuring clearing, when lettering the next lower line, a wet upper line lettered through any of the slots and also to clear the circles drawn through the holes 18 and 19. However, I found that the width of the groove 21 sufficient to clear the upper line lettered through the slots 14 and 15 produces a guide of well-balanced proportions, and is sufficient for the average run of drafting lettering.

For lettering in pencil, the guide is placed on the paper with the ink clearing groove 21 away from the paper, see Figs. 1 and 2, and lettering is done in the same manner as with a guide not having such an ink clearing groove. However, the presence of said groove has advantages even in pencil lettering, since the thinning out of the body 10 along the slot 12 makes pencil lettering easier and more pleasant, while the thickness of the body along its longitudinal edges prevents it from slipping under the T-square, which slipping would be very annoying if the entire guide were made of the same thickness as it is along the slot 12.

For lettering in ink, the guide is turned end-over-end to place the ink clearing groove 21 against the paper, as shown in Fig. 3, whereupon the lettering is done with the same use of the slot 12 and holes 18 and 19 as in pencil lettering, the only difference being that the longitudinal order of the slot portions will now be reversed, the slot portion 17 being on the right instead of on the left as in pencil lettering.

Means are provided enabling the user to arrange lettering characters vertically and to provide neat vertical margins in notes, said means being exemplified by a number of lines

22 perpendicular to the straight edge 11 and provided on the bottom surface 10b of the body 10. By such an arrangement said lines are not interrupted by the groove 21 and extend all the way to the edges of the slot 12. I prefer to space said lines approximately $\frac{1}{2}$ " apart.

Means are also provided enabling the user to space note lines uniformly at a number of selective predetermined distances from each other. Such means are exemplified by a number, in the present embodiment two, of horizontal lines 23 and 24 which are parallel to the straight edge 11, and are provided on the surface 10b of the body 10. The lower line 24 is provided at a distance from the edge 14a equal to $1\frac{1}{2}$ times the width of the slot 14 plus $\frac{1}{2}$ of the allowance for pencil, while the line 23 is spaced from the line 24 at a distance equal approximately to one half the width of the slot 14. By virtue of such a construction the note lines lettered through the slot 14 may be selectively spaced at distances of $\frac{1}{2}$, 1, $1\frac{1}{2}$, and 2 times that of the width of slot 14. The edges of the guide at the slot 12 as well as holes 18 and 19 may be slightly chamfered as shown at 25.

Thus there is provided an improved lettering guide with the aid of which the objects of the present invention and a number of additional advantages are attained.

I claim:

1. In a lettering guide, a body, a straight edge on said body, said body being provided with at least three lettering slots of different widths parallel to said edge, two of said slots having their lower edges forming a continuation of each other, and two slots having their upper edges forming a continuation of each other.

2. In a lettering guide, a body, a straight edge on said body, said body being provided with at least three lettering slots parallel to said straight edge, the first of said slots having an arbitrarily selected width, the second of said slots having its lower edge forming a continuation of said first slot and the width equal to approximately once and a half that of the first slot, said third slot having its upper edge forming a continuation of said second slot and the width equal to approximately twice that of said first slot.

3. In a lettering guide, a body, a straight edge on said body, said body being provided with four longitudinally adjacent slots of different width and parallel to said straight edge, said slots providing for lettering therethrough lettering characters of approximately .10", .15", .20", and .25", respectively, the .10", .20", and .25" slots having their axes along the same straight line.

4. In a lettering guide, a body, a straight edge on said body, said body being provided with four longitudinally adjacent slots of different width and parallel to said straight edge, said slots providing for lettering therethrough lettering characters of approximately .10", .15", .20", and .25", respectively, the .10", .20", and .25" slots having their axes along the same straight line, the .10" and the .15" slots having their lower edges along the same straight line.

5. In a lettering guide, a body, a straight edge on said body, said body being provided with four longitudinally adjacent slots of different width and parallel to said straight edge, said slots providing for lettering therethrough lettering characters of approximately .10", .15", .20", and .25", respectively, the .10", .20", and .25" slots having their axes along the same straight line,

the .10" and the .15" slots having their lower edges along the same straight line, and the .15" and .20" slots having their upper edges along the same straight line.

6. In a lettering guide, a body, a straight edge on said body, said body being provided with four longitudinally adjacent slots of different width and parallel to said straight edge, said slots providing for lettering therethrough lettering characters of approximately .10", .15", .20", and .25", respectively, the .10", .20", and .25" slots having their axes along the same straight line, two round openings for drawing circles of approximately one half an inch in diameter and three eighths of an inch in diameter being provided on said body, with the centers of said openings being disposed on said axis line.

7. A reversible ink and pencil lettering guide comprising a body having a straight edge, said body being provided with a combination slot extending along said straight edge and having its longitudinal edges parallel thereto, said combination slot being composed of a plurality of longitudinally adjacent slot portions merging into one another at their adjacent ends, at least one of said slot portions having length sufficient to letter therethrough a plurality of lettering characters without shifting the guide, said slot portions having different but mutually correlated widths and a correlated axial arrangement corresponding to those of lettering characters of at least one predetermined font thereof; said body being further provided on one of its surfaces over said slot with a straight ink clearing groove, said groove being disposed substantially parallel to said straight edge and running to the very edge of said body at least

at one of its ends, whereby said guide is adapted to bear against the paper with its one entire surface for pencil lettering, and to have all of its edges at said combination slot raised from the paper when the guide is turned over for ink lettering, with none of the characters lettered through the slot being reversed by such turning over of the guide, two lines being provided parallel to the straight edge on the surface of the body opposite to the surface on which the ink clearing groove is provided, said lines adapted to be used for setting the guide with its slot at one of a number of predetermined distances from a line of a lettered note, the ink clearing groove having width to extend transversely of the guide beyond both of said lines to ensure that a lower line of characters can be lettered in ink while the upper line of the characters is still wet, without smearing said upper line, at least when using the narrowest slot and the narrowest spacing between the note lines.
